UNITED STATES PATENT OFFICE.

WILLIAM T. GALLT, OF PORT BYRON, NEW YORK.

SHIRT-LACE.

SPECIFICATION forming part of Letters Patent No. 314,661, dated March 31, 1885.

Application filed July 5, 1884. (No model.)

To all whom it may concern:

Be it known that I, WILLIAM T. GALLT, of Port Byron, in the county of Cayuga and State of New York, have invented a certain new and useful Improvement in Shirt-Laces; and I do hereby declare that the following is a full, clear, and exact description of the same, reference being had to the accompanying drawings, in which—

10 Figure 1 is a front view of a shirt with my improvement applied thereto. Fig. 2 is a front view of a portion of the lacing.

15 My improvement relates to fancy shirts with an ornamental lacing in front which closes and secures the sides.

20 The invention consists of a lacing composed of a single piece of cord looped to form button-holes on opposite sides, in combination with a shirt-front provided with buttons on opposite sides, over which the loops button, the lacing resting wholly outside and being removable from place, as hereinafter more fully described.

25 In the drawings, A shows a shirt of usual form, being open in front, and having a row of buttons, *a a*, on each side of the bosom-opening, as usual.

30 B is the lacing, which is made of cord of any desired kind and color. It is made from a single piece, and is doubled to produce the loops *b b* on opposite sides, is knotted in the center, as shown at *c*, is then carried down, forming the connecting-length *d*, and is then looped again till the whole lacing is complete. This

35 forms a lacing from a single cord, with as many loops as there are buttons, and each pair of loops united with the next pair by a connecting-length, and the whole forming a device that can be applied or removed at pleasure. In some cases I shorten the button-holes 40 by closing a part of the loop by stitching, as shown at *f*, so that the button-hole is fitted to hold on the button, while the loop is made of the necessary length to extend from button to button across the shirt.

45 The advantages of this invention are that while the lacing serves the same purpose as ordinary lacings or loops that are permanently sewed or otherwise attached to the shirt, it is removable all in one body for the purpose of 50 either washing the shirt or the lacing, or for other purposes, and is easily replaced by a new lacing, or where it is desired to use a lacing of a different color.

55 What I claim as new is—

The lacing made from a single length, consisting of the opposite loops *b b*, knots *c c*, and connecting-lengths *d d*, in combination with a shirt-front provided with buttons on opposite sides, over which the loops button, as shown 60 and described, and for the purpose specified.

In witness whereof I have hereunto signed my name in the presence of two subscribing witnesses.

WM. T. GALLT.
